UNITED STATES PATENT OFFICE.

HENRY F. PEARCE, OF SCRANTON, PENNSYLVANIA.

DESIGN FOR A LID FOR MINERS' LAMPS.

SPECIFICATION forming part of Design No. 30,992, dated June 13, 1899.

Application filed May 8, 1899. Serial No. 716,027. Term of patent 7 years.

To all whom it may concern:

Be it known that I, HENRY F. PEARCE, a citizen of the United States, residing at Scranton, in the county of Lackawanna and State of Pennsylvania, have invented and produced a new and original Design for Lids for Miners' Lamps, of which the following is a specification, reference being had therein to the accompanying drawings.

10 This design is intended particularly to be applicable to the lid-piece of miners' lamps. Its principal features are illustrated in the drawings, in which—

15 Figure 1 is a top plan view of the lid of a miner's lamp, showing my new design. Fig. 2 is an under side view of the same. Fig. 3 is a sectional view taken on the line $x-x$ of Fig. 1. Fig. 4 is a similar sectional view taken on the line $y-y$ of Fig. 1. Fig. 5 is a 20 side elevation of a lid made according to my new design.

As shown in the drawings, the leading or material features of my new design consist of a substantially hemispherical dome having 25 embossments or corrugations A A in the semblance of a pair of miners' picks crossing one another centrally at the summit of the dome,

a slightly-greater elevation being at C, where the eyes of the crossed picks apparently coincide. Arranged concentrically about the 30 elevation C, in the four angles outlined by the crossed picks aforesaid, are four similar embossments B B B B in semblance of miners' picks without the handles removed, each of the handles pointing toward the summit C of 35 the dome. The rounded embossment C surmounts a square central embossment D.

It is apparent that this design is also applicable to ornamental objects and lids of other articles as well as to lids of miners' 40 lamps, with which I use it.

Having described my invention, what I claim as new, and desire to secure by Letters Patent, is—

The design for a lid-piece for miners' lamps 45 or other articles as herein shown and described.

In testimony whereof I affix my signature in presence of two witnesses.

HENRY F. PEARCE.
